UNITED STATES PATENT OFFICE.

FRANK EILERS, OF FORT WAYNE, INDIANA, ASSIGNOR TO TOKHEIM OIL TANK AND PUMP COMPANY, A CORPORATION OF INDIANA.

PISTON-HEAD.

1,337,982.

Specification of Letters Patent. Patented Apr. 20, 1920.

Application filed November 1, 1919. Serial No. 335,025.

To all whom it may concern:

Be it known that I, FRANK EILERS, a citizen of the United States of America, and resident of Fort Wayne, in the county of 5 Allen and State of Indiana, have invented certain new and useful Improvements in Piston-Heads, of which the following is a specification.

This invention relates to improvements in 10 piston heads of the valvular type for displacement pumps of that class used in dispensing liquid in unit quantities measured by the length of stroke of the piston. The object of the improvement is to provide an 15 inexpensive, durable and efficient piston head with parts so constructed and arranged as to be easily assembled.

The object of the invention is accomplished by the construction illustrated in the 20 accompanying drawings in which,—

Figure 1 is a transverse section of a pump cylinder in which is shown a top view of the improved piston head, parts thereof being broken away; and

25 Fig. 2 is an elevation of the same shown partly broken away and in section.

Similar characters of reference indicate corresponding parts throughout the views and having reference now to the same:

30 1 is a pump cylinder of usual construction, and 2 is a pump rod, the lower end 3 of which is threaded and provided with nuts 4 and 5. The piston head is comprised of a cup-shaped sustaining member 6 having 35 an annular series of passage-ways 7 that extend through its curved outer part near its perimeter; a flexible valvular member 8 lying within the hollow of the sustaining member so as to normally close the passage-ways 40 therein and with its perimeter 9 extending beyond that of the sustaining member and bearing against the inner wall of the cylinder; and an expanding spider 10 tending to hold the valvular member closed over

45 the passage-ways in the sustaining member and with its perimeter pressed against the walls of the cylinder. Also a retaining disk 11 is arranged concentrically with the sustaining member, valvular member and spider 50 fixedly between the nuts 4 and 5, the disk being positioned above the spider so that the central portion of the latter is held tightly against the corresponding part of the valvular member. The sustaining member 55 is metallic and rigid on the pump rod,

its outer perimeter fitting loosely within the pump cylinder so as to move freely therein; the valvular member is of leather or other suitable flexible material; and the spider is made preferably of spring sheet metal 60 shaped with an annular series of bowed arms 12, each of which has a wide foot 13 formed at its outer extremity, and a corresponding annular series of tongues 14 that intervene respectively between the arms and terminate 65 within the diameter of the annular series of passage-ways in the sustaining member. The feet 13 bear against the valvular member 8 near its perimeter and the corresponding arms 12 bridge that annular portion of 70 the valvular member that lies over the series of passage-ways so that the outer edge of the valvular member is pressed by the feet against that annular portion of the sustaining member beyond the series of passage-ways and also against the adjacent wall of 75 the cylinder. The tongues hold the central part of the flexible valvular member against that corresponding face of the sustaining member that lies within the annular series 80 of passage-ways. Thus, the central portion of the valvular member and its outer marginal portion are spring pressed in position against the corresponding parts of the sustaining member while its intervening annular part that covers the passage-ways, being 85 bridged by the arms, is unrestrained by direct pressure of the spider so that it may be raised by the liquid in its passage under pressure through the piston head. 90

In the operation of the invention the lower end of the pump cylinder is connected with the usual suction line provided with a foot valve (not shown) so that liquid drawn into the cylinder therethrough is prevented 95 from retracting. As the piston is drawn upwardly in the cylinder by the action of the pump-rod the valvular member is held closed over the passage-ways and with its perimeter bearing against the cylinder wall 100 and the cylinder thereupon becomes filled with liquid drawn thereinto through the suction line. During the downward stroke of the piston head liquid previously drawn into the cylinder beneath the piston head flows 105 through the passage-ways and between the valvular and sustaining members, the former being lifted from seated position by pressure of the liquid as it thus escapes through the piston head. During the subsequent rise of 110

the piston the liquid previously admitted therethrough is raised in the cylinder and discharged therefrom in the usual manner and concurrently an additional charge of liquid is drawn into the cylinder and is discharged by repetition of the operation.

The efficacy of the piston head thus constructed is especially desirable when the pump is depended upon also to effect measurement of the liquid by gaging the extent of the piston stroke thereof in the customary manner. The responsiveness of the valvular member in closing the passage-ways through the sustaining member and its intimate contact with the wall of the cylinder during the upper stroke of the piston is enhanced by the constant spring pressure of the tongues and feet of the spider, and the readiness of the valvular member in admitting the passage of liquid through the piston during its downward stroke is effected by forming the spider arms so as to bridge the annular portion of the valvular member that closes over the passage-ways, thus permitting the valvular member to act unrestrained during the upward flow of liquid through the passage-ways.

What I claim is:—

1. In a valvular piston for a displacement pump having a cylinder and pump rod, a cup-shaped sustaining member fixed upon the rod and fitting loosely in the cylinder and having an annular series of passage-ways extending therethrough; a flexible valvular member lying within the hollow of the sustaining member so as to normally close the passage-ways therein and with its perimeter extending beyond that of the sustaining member and bearing against the inner wall of the cylinder; and an expanding spider having radially disposed bowed arms the outer ends of each pressing the corresponding outer portion of the valvular member against the cylinder wall, and having also radially disposed tongues intervening between said arms respectively tending to hold the central part of the valvular member in contact with the corresponding face of the sustaining member, the annular portion of the valvular member extending between the outer ends of the tongues and arms and covering the passage-ways in the sustaining member, being free from direct pressure of the spider.
2. In a valvular piston for a displacement pump having a cylinder, a piston head including a pump rod and a sustaining mem-

ber having an annular series of passage-ways extending therethrough; a flexible valvular member adapted to close the passage-ways, its perimeter extending beyond that of the sustaining member and bearing against the wall of the cylinder; and a spider tending to hold the valvular member in contact with the cylinder wall.

3. A valvular piston head for displacement pumps having a cylinder, a perforated sustaining member loosely fitting the cylinder, and a spring pressed flexible valvular member for closing the perforations of the sustaining member, the outer perimeter of the valvular member extending beyond that of the sustaining member and bearing against the cylinder wall.

4. In a valvular piston head for a displacement pump having a cylinder, a perforated sustaining member including a pump-rod attached thereto, a flexible valvular member adapted to close the perforations, its perimeter having bearing relation with the wall of the cylinder; a spider having radial arms the outer ends of which tend to hold the perimeter of the valvular member against the cylinder wall; and means in connection with the rod for holding the spider and members in co-operative relation.

5. In a valvular piston head for a displacement pump having a cylinder, a sustaining member having a concentric annular series of passage-ways extending therethrough, its perimeter fitting loosely within the cylinder; a flexible valvular member adapted to close the passage-ways, its perimeter having bearing relation with the wall of the cylinder; a spider having radial arms and tongues intervening respectively therebetween adapted to press the marginal portion of the valvular member against the cylinder wall and that portion of the valvular member lying within the series of passage-ways against the sustaining member and leaving the annular portion of the valvular member covering the passage-ways free to rise therefrom without direct obstruction of the spider; and means including a pump rod for securing the spider and members in co-operative relation.

In testimony whereof I affix my signature, in presence of two witnesses.

FRANK EILERS.
